Primary Examiner — Paula Allen Greene

(74) *Attorney, Agent, or Firm* — Drinker Biddle & Reath LLP

(57) **CLAIM**

The ornamental design for the speaker for automobile, as shown and described.

DESCRIPTION

FIG. 1 is a perspective view of a speaker for automobile showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the speaker for automobile is included for the purpose of illustrating portions of the speaker for automobile and forms no part of the claimed design.

1 Claim, 7 Drawing Sheets
